UNITED STATES PATENT OFFICE.

AARON I. GAUMER, OF SALT LAKE CITY, UTAH.

DESIGN FOR A KITCHEN-CABINET.

SPECIFICATION forming part of Design No. 35,347, dated November 26, 1901.

Application filed October 24, 1901. Serial No. 79,879. Term of patent 14 years.

To all whom it may concern:

Be it known that I, AARON I. GAUMER, a citizen of the United States, residing at Salt Lake City, in the county of Salt Lake and State 5 of Utah, have invented and produced a new and original Design for Kitchen-Cabinets, of which the following is a specification.

My invention relates to kitchen-cabinets, and my object is to produce a new and original design for the same which is both useful and ornamental.

In the accompanying drawings, Figure 1 is a front view, and Fig. 2 a top plan view, of a kitchen-cabinet embodying my new design.

15 The leading or material feature of the design resides in its novel and peculiar configuration, the base portion being of cylindrical form and provided with rectangular front and rear portions, the former having a door in its 20 face; also, in the large cylindrical can centrally surmounting the cylindrical body portion and in the two series of smaller cans arranged at opposite sides of the large can, said smaller cans being arranged in curved series 25 and varying in height and diameter, the smallest cans being in front and the largest in the rear, with the intermediate-sized ones correspondingly arranged between the extremes mentioned.

30 Minor features of the design reside in the

tapering lower ends of the small cans and in the conical tops thereof and of the large can; also, in the vertical series of rectangular figures arranged centrally of the large can and the circular figures arranged centrally of said 35 rectangular figures.

Referring to the drawings in detail, 1 designates the cylindrical base portion; 2, the rectangular front portion; 3, the rectangular rear portion, and 4 the door in the face of the 40 front portion.

5 designates the large can; 6, the conical top thereof; 7, the vertical series of rectangular figures, and 8 the circular figures arranged centrally of the rectangular figures. 45

9 designates the smaller cans of graduated size, 10 the tapering lower ends, and 11 the conical tops of the same.

Having thus described the invention, what I claim as new, and desire to secure by Letters 50 Patent, is—

The design for a kitchen-cabinet, substantially as herein shown and described.

In testimony whereof I affix my signature in the presence of two witnesses.

AARON I. GAUMER.
